UNITED STATES PATENT OFFICE.

WILLIAM E. HALE, OF WALPOLE, MASSACHUSETTS, ASSIGNOR TO BIRD & SON, INC.,
OF EAST WALPOLE, MASSACHUSETTS, A CORPORATION OF MASSACHUSETTS.

ROOFING.

Application filed May 2, 1924. Serial No. 710,028.

This invention relates to an improved roofing or exterior construction, and shingle, and the objects of the invention are to secure a durable, efficient, slight construction of roofs and the like with a minimum expenditure of time, labor, trouble and material. Less than one hundred and fifty square feet of roofing material may be made to cover one square or one hundred square feet 10 of roof by proceeding in accordance with this invention.

The construction and method are best explained in connection with the accompanying illustrative drawings, in which like 15 numerals represent like parts.

In the drawings:

Fig. 1 is a plan view of my preferred type of shingle;

Fig. 2 is an edge elevation of the same;

Fig. 3 is a perspective view, partly in section, illustrating the connection of a shingle to a subjacent shingle; and

Fig. 4 is a plan view of a portion of roof or exterior wall embodying my improved construction.

Referring to the drawings:

Fig. 1 shows a shingle or member 10 provided with a locking strip 12 attached to the shingle by staples 14, and a bent corner portion 16, though if desired, members not having the pre-bent corner may be used and bent into the form shown as they are laid. In the latter case the member is first placed backside out and may be then bent while being put in its proper position on the roof. The result is substantially the same as when shingles with previously bent corners are used.

The locking strip 12 may be of any suitable material, depending somewhat on the type and material of the roofing members themselves. In case the latter are of a flexible prepared roofing type, I preferably employ a flexible locking strip made of saturated felt similar to that used in making the roofing material. This insures a life at least equal to that of the roofing material. It is not essential, however, that a flexible key strip be employed but if not of the flexible type it should ordinarily be slightly bent. The position of the locking strip, with reference to the member 10 to which it is attached, is determined by the extent it is desired to have the members 10 lap as herein-after explained. If the locking strips 12

are not attached until the shingles are laid (in such case the staples or nails may or may not extend into the sheathing) it is desirable to have them of a definite and uniform length in order to simplify their positioning when being attached to such shingles. It is preferable and easier however to use my shingle with a pre-attached strip or locking element, as illustrated in Figs. 1 and 2. This insures perfect alignment of the shingles on the roof since the locking strip is always fixed and held in a positive position with reference to the shingle to which it is affixed. The locking strip, being attached to the main or flat part of the shingle by any suitable means, does not interfere with shipping or handling of the shingles, which may be conveniently packed, or piled, and applied to the roof.

Figs. 3 and 4 clearly illustrate the construction. 20 is a wooden or other suitable sheathing, upon which the members 10 are held. It is usually preferable to employ a starting strip (not shown) extending along the eave or lower edge of the surface to be covered. The first or lowest course of the members 10 is then placed in position by sliding the bent portion 16 under the lower edge of the starting strip. The adjacent corners of the members 10 are then nailed down (or otherwise fastened) and held by nails 22, as clearly shown in Fig. 4. The next course of members 10 is then applied, the bent-up portions 16 being inserted under the locking strips attached to the subjacent shingles and the members 10 pushed upwardly until the inside of the bend 18 of each shingle comes adjacent to the locking strip attached to its respective subjacent shingle. At the ridge or hip of the roof the members 10 may be broken off, severed, or simply bent over, and suitable ridge or hip covering (not shown) applied. Due to the locking strip (in its preferred form) having considerable surface and being under the edges of the adjacent shingles overlapping its ends in addition to being attached to the overlapping shingle, it is securely held and it in turn holds down the lower end portion 16 of the overlying member 10, presenting a broad flat surface to the portion 16 and preferably extending nearly down to the bend 18, where it will do the most effective work; that is, the locking strip holds the bent over portion 16 at the line of greatest strain and a shearing

stress is required in order to directly lift the shingle or tear it from its place, as any attempted curl or upward lift of the roofing material comes against the broad flat surface of the locking strip and opposite the points where the strip goes under and is overlapped by the edges of the adjacent pieces of roofing. This construction also permits a slight (parallel to the roof), of the bent up portion 16 and its roofing member 10 which allows or and its roofing member 10 which allows or compensates for unequal expansion, or contraction of the sheathing and roofing members. The position of the locking strip itself, 15 however, is fixed with respect to the adjacent shingles as well as the shingle to which it is attached. The bent up portions 16 are free to move a sufficient distance to counteract the effects of contraction or expansion of the 20 sheathing 20 and the members 10 and thereby prevent the roof from becoming unsightly or leaky. The construction described forms a durable roof or wall covering, with its members effectively interlocked so as to resist the weather and compensate for expansion or contraction of the sheathing or members by allowing a slight movement or slip 25 relative to one another, and still does not allow rain or snow to beat under the lower edges or corners of the shingles, thus effectively securing the objects previously set forth.

What I claim is:

1. As an article of manufacture, a shingle 30 formed from pliable slate-surfaced fibrous

material having but one corner portion bent under, said shingle having permanently affixed upon its upper surface adjacent the diagonally opposite corner means adapted to hold down the bent-under portion of a similar overlying shingle. 40

2. As an article of manufacture, a shingle formed from pliable slate-surfaced fibrous material having but one corner portion bent under, said shingle having permanently affixed upon its upper surface adjacent the diagonally opposite corner means adapted to slidably engage and hold down the bent-under portion of a similar overlying shingle. 45

3. As an article of manufacture, a shingle 50 formed from pliable slate-surfaced fibrous material having but one corner portion bent under, said shingle having permanently affixed upon its upper surface adjacent the diagonally opposite corner an attached piece of 55 suitable material adapted to engage and hold down the bent-under portion of an overlying shingle.

4. As an article of manufacture, a shingle 60 formed from a square of pliable slate-surfaced fibrous material having but one corner portion bent under, said shingle having permanently affixed upon its upper surface adjacent the diagonally opposite corner an attached strip of suitable material adapted to 65 extend across and hold down the bent-under portion of an overlying shingle, the ends of said strip being adapted to project under the edges of the adjacent shingles.

WILLIAM E. HALE.
